UNITED STATES PATENT OFFICE.

OLIVER PERRY SCOTT, OF QUINCY, ILLINOIS.

PRINTING AND VIGNETTING FRAME.

SPECIFICATION forming part of Letters Patent No. 298,901, dated May 20, 1884.

Application filed April 28, 1883. (No model.)

To all whom it may concern:

Be it known that I, OLIVER PERRY SCOTT, of Quincy, in the county of Adams and State of Illinois, have invented new and useful Improvements in Tinting Photographs, of which the following is a specification, reference being had to the accompanying drawings, illustrating the invention, in which—

Figure I is a perspective representation of a photographer's printing-frame with my improved tinting device attached; Fig. II, a longitudinal vertical central sectional elevation of Fig. I; Fig. III, a cross-section of Fig. II on line x.

15 The object of the present invention is to provide better means for tinting or vignetting photographs.

The nature of the invention in brief consists of a special construction of an adjustable 20 housing placed over the face of the printing-frame, and provided with means for clamping the tissue-paper to the housing, whereby different tints may be given to photographs by simply adjusting the housing to or from the 25 printing-frame, as the whole is herein fully described and shown.

A A represent the sides, B B the ends, and C C the clamping-blocks, of an ordinary 30 photographer's printing-frame, which is a well-known apparatus in the art.

A housing, E, which is made of light metal or other suitable material, is formed with a hole through its face corresponding in size to the face-opening of the frame, and, with sides 35 F and ends G, is placed over the frame, as shown. The ends G are slotted out, as shown at H, that the housing may be adjustable on screws a a, projecting out from the ends B of the frame and held in a fixed position relative 40 to the face of the frame by means of thumb-screws I I.

To the face of the housing E, at d, is hinged a skeleton frame, K, which serves the purpose

of clamping tissue-paper b to the face of the housing by means of an intermediate card-board, M. The skeleton frame, being made of spring metal, is held shut against a stop, N.

In the foregoing one means has been shown to adjust and hold the housing E in position, which will serve the purpose, and is very simple; but as it is not very convenient to move the housing E out from the frame, a spring, L, is attached to the inside of the housing over each end piece B, so as to bear on the frame and force the housing out so soon as the thumb-screws I I are loosened.

I am aware that an adjustable housing has been heretofore shown in the patent of Van Wagner and Griswold, No. 150,479, and I do not broadly claim an adjustable housing, limiting my claims to the special construction by means of which I obtain a compact and easily-operating apparatus.

Having thus described my invention, what I claim is—

1. The combination, with a printing-frame, of a housing or vignetting attachment fitting over said frame and adapted to be vertically adjusted thereon, having the central opening and the skeleton frame, the said wire frame being attached to the housing and operating to hold the paper, substantially as described.

2. In combination with a printing-frame, a vignetting attachment consisting of a housing fitting over said frame, and provided with a central opening, slotted sides, and thumb-screws for the adjustment of the attachment, the skeleton frame for holding the paper in place, and the spring or springs beneath the said vignetting attachment, to force it upward from the frame, substantially as described.

OLIVER PERRY SCOTT.
